ATTORNEY.

UNITED STATES PATENT OFFICE.

FRANK L. FULLER, OF DETROIT, MICHIGAN.

KNIFE GUARD.

Application filed December 6, 1923. Serial No. 678,845.

To all whom it may concern:

Be it known that FRANK L. FULLER, a citizen of the United States, residing at Detroit, in the county of Wayne and State 5 of Michigan, has invented certain new and useful Improvements in Knife Guards, of which the following is a specification.

This invention relates to improvements in a paring knife guard, the object of which 10 is to provide a guard which is spaced from the cutting edge of the knife and firmly held in such spaced relation. The construction of the guard is such that the cutting edge of the knife is so located with respect to the 15 guard as to enable one to use the knife for paring fruit or vegetable with the least amount of waste. No matter how much the knife is worn the guard fits on the knife blade so that parings of the same thickness 20 are cut away. With a guard of this character any small curvature in the blade of the knife does not affect the utility of the device and therefore the paring knife may be used until the same is nearly worn away.

25 The prior art discloses numerous forms of paring knife guards, some of which are adapted to be clamped along the cutting edge of the knife, but my improved guard is a decided improvement over these. In 30 my invention I provide a tubular guard member which is formed of one piece of blanked stock, the stock cut in such a way as to allow the material for the ears to project rearwardly from the rolled tubular portion. An advantage of this tubular portion 35 is that the knife guard may be made of thinner gauge metal and yet possesses the necessary strength and rigidity to prevent the same from becoming bent or forced out 40 of shape, which would necessarily destroy the utility of the device. Another advantage of having this tubular guard member extend the full length of the device is in creating a spring tension on the ears so that 45 the attachment may be firmly clamped upon the knife blade. The spring is distributed throughout the entire length of the tubular portion.

To sharpen the knife, it is necessary to 50 merely slip the guard off at which time the knife edge may be sharpened in the usual way. As the guard is replaced on the knife blade it will assume the position as before, no final adjustments being necessary,

In the drawings:

Fig. 1 is a perspective view of the knife 55 with my guard attached thereto.

Fig. 2 is a section on the line 2-2 of Fig. 1.

Fig. 3 is a section on the line 3-3 of Fig. 1.

Fig. 4 is a detail showing the blank of which the guard is made.

A knife blade *a* is provided with a sharpened cutting edge *b*, and a handle *c*. This 65 is the ordinary construction of the paring knife most generally used for vegetable paring.

My improved guard is formed first by blanking the same from flat stock, as shown 70 in Fig. 4. At both ends of the blank are a pair of ears *d* and *d'*. The blank is rolled so as to form a tubular member designated *e*, and the ears *d* and *d'* extending to the rear. The guard is formed of spring metal and as 75 the guard is slipped on the knife blade the ears *d* and *d'* will grip the blade and prevent ordinary displacement of the same.

At each end of the guard there is provided 80 an inwardly extending lip *g* which extends approximately at right angles to the longitudinal axis of the tubular portion. The lower edge of said lip is beveled as at *h* and the knife blade is wedged between the bevelled edge of said lip and the bottom ears *d'*. 85

In Fig. 2, I have shown by the dotted lines 90 designated *x*, the normal position of the upturned edges *v* of the tubular member when the same is removed from the blade. As the ears *d* and *d'* are forced onto the knife blade, the ears will be forced apart and the edges *v* of the guard member will be forced together and assume the full line position as shown. The result is that the entire length 95 of the tubular member assists in providing spring tension for forcing the ears *d* and *d'* together, thereby securely clamping the knife blade between the ears.

The lower ear *d'* is offset from the tubular 100 guard member as shown in Fig. 2, and then is bent and runs parallel with the upper ear *d*. This forms a shoulder *k* which acts as a stop for the knife blade. The lip *g* is bent out from this offset portion of the ear *d'* and the inclined surface *h* together with 105 the rest of the ear *d'* forms a guide for guiding the knife blade as the same is wedged between the lip and ear until the

cutting edge of the knife abuts the shoulder or stop *k*.

In referring to Fig 2 it will be seen that the lower portion of the tubular guard is flattened as at 10 for a distance of approximately .07 of an inch; as a result, a slight variation in the position of the cutting edge of the knife blade will not affect the thickness of the paring as the distance between the cutting edge and the guard remains constant within this limit. As the knife blade is sharpened and worn, it does not retain its straight edge and some new knives are also made with slightly curved cutting edges. If it were not for the flattened underside of the guard it would be impossible to efficiently use a knife blade that has a curved cutting edge, or one that has become worn because the thickness of the paring would be variable.

What I claim is:

1. An attachment for a paring knife, comprising a tubular guard member provided with a flattened portion, and a pair of ears bent out therefrom, said ears adapted to grip the knife blade, one of said ears being provided with a shoulder to properly locate the cutting edge of said blade with respect to the flattened portion of said guard.
2. An attachment for a paring knife, comprising a tubular guard member provided with a flattened portion and a pair of ears integrally formed with said tubular portion, said ears being offset and extended rearwardly of said tubular portion and adapted to grip the knife blade, the offset portion forming a shoulder to provide a stop for the knife blade to properly locate the flattened portion of said guard with respect to said cutting edge of said knife blade.
3. An attachment for a paring knife, comprising a tubular guard member provided with rearwardly extending ears and a flattened underside portion, said ears being offset and adapted to grip a knife blade, said offset ears forming a shoulder to act as a stop for the knife blade to properly locate the tubular guard with respect to the cutting edge of said knife blade, and lips bent at right angles to the longitudinal axis of said tubular guard to act as spacers between the flattened underside portion of said guard and blade as the guard is slipped on the knife to properly space the tubular guard from the cutting edge of the knife blade.
4. An attachment for a paring knife, comprising a tubular guard member provided

with rearwardly extending ears and a flattened portion, said ears being offset to form a shoulder and adapted to grip the knife blade, the edge of said knife blade adapted to abut the shoulder formed by said offset ears to properly locate the blade with respect to the flattened portion of said guard, and lips carried by said guard member and bent inwardly from said offset portion at substantially right angles to the longitudinal axis of the guard member, said lips having an inclined edge, the knife blade adapted to be wedged between said inclined edges of the lips and the lower ears carried by said tubular guard for spacing the guard from said cutting edge.

5. An attachment for a paring knife, comprising a tubular guard provided with a flattened underside and having a pair of ears bent out therefrom, said ears adapted to grip the knife blade to clamp the guard thereto, one of said ears being provided with a shoulder to locate the cutting edge of said knife blade near said flattened portion of the guard, and means for spacing the said cutting edge a constant distance from the flattened underside portion of the guard member within predetermined limits irrespective of the curvature of said cutting edge.

6. An attachment for a paring knife, comprising a split tubular guard the edges of which are turned up and arranged to interlock to limit the expansion of said tubular member, the said tubular guard normally contracted and the turned up edges spaced apart, and ears projecting from the tubular guard in substantial parallelism, the said ears adapted to grip a knife blade therebetween and the entire tubular guard exerting a spring tension on said ears to clamp the knife blade in place.

7. An attachment for a paring knife, comprising a split tubular spring guard provided with projecting ears the said spring guard tending to force the ears together, the said ears adapted to be spread when a knife blade is inserted therebetween, thereby causing the split tubular spring guard to expand, the inherent spring tension of the entire length of said guard resisting said expanding action to clamp the knife blade firmly between the ears.

In testimony whereof I affix my signature.

FRANK L. FULLER.
